F. JEWELL.
RAILROAD SWITCH.

No. 554,026.

Patented Feb. 4, 1896.

UNITED STATES PATENT OFFICE.

FRANK JEWELL, OF BATAVIA, NEW YORK, ASSIGNOR OF ONE-HALF TO
GEORGE F. BURNS, OF SAME PLACE.

RAILROAD-SWITCH.

SPECIFICATION forming part of Letters Patent No. 554,026, dated February 4, 1896.

Application filed March 12, 1895. Serial No. 541,488. (No model.)

To all whom it may concern:

Be it known that I, FRANK JEWELL, a citizen of the United States, residing at Batavia, in the county of Genesee and State of New York, have invented a new and useful Railroad-Switch, of which the following is a specification.

This invention relates to an improvement in railroad-switches, and the object of the invention is to simplify and improve the construction thereof, so that it will be impossible to derail engines or cars passing through the same, which will prevent such cars or engines from injuring or throwing the switch out of order, and which will be simple and inexpensive in construction, strong and durable, and which will possess numerous advantages over the ordinary form of switch, as will hereinafter appear.

20 The invention consists in certain novel features and details of construction and arrangement of parts, as hereinafter fully described, illustrated in the drawings, and finally pointed out in the claims hereto appended.

25 In the accompanying drawings, Figure 1 is a plan view of a railway-switch constructed in accordance with my improvements shown closed. Fig. 2 is a similar view with the switch thrown open. Fig. 3 is a transverse 30 vertical section taken near the ends of the split rails with the switch closed. Fig. 4 is a similar view with the switch opened. Fig. 5 is a detail perspective view of one of the operating rock-shafts. Fig. 6 is a similar view 35 of one of the castings for supporting the rails and receiving the end of a rock-shaft. Fig. 7 is a perspective view of a portion of the switch-operating mechanism, showing also the means for locking the switch and for operating the semaphore.

Similar numerals of reference indicate corresponding parts in the several figures of the drawings.

Referring to the drawings, 1 and 2 indicate 45 two split rails, 1 being the terminal of one of the siding-rails and the other, 2, forming a portion of the main track. The split rails 1 and 2 are upheld and supported at one end by the usual ties, to which they are fastened 50 by spikes in the usual manner. The opposite or tapering ends of the split rails are left free

both vertically and laterally, with the exception of an interposed spring connection composed of two bars or angle-irons 3 secured one to the inner face of each split rail, from whence they extend inwardly, and are connected by a bolt 4, having a spiral spring 5 disposed around the same, as shown. The outer ends of the bars or angle-irons 3 are bolted rigidly to the tapering extremities of the rails and their inner adjacent ends are deflected at right angles and formed with perforations slightly larger than the shank of the bolt 4, which passes through said perforations. This allows relative vertical movement of the adjacent ends of the bars or irons 3, while the spring interposed between the inner bent ends of said bars operates to force the same apart and to hold the tapered extremities of the rails in contact with the rails to which they lie adjacent.

6 and 7 indicate short cam rolls or shafts which are arranged in corresponding series, the rolls 6 underlying the siding-rail 1 and the rolls 7 underlying the main rail 2. The inner adjacent ends of each pair of rolls 6 and 7 are connected by means of a bar 8, which is riveted thereto at 9, thus serving to rigidly connect said rolls and communicate motion from one to the other, the rolls 6 and 7 and the bar 8 practically forming a rock-shaft operating beneath the rails. Each roll 7 is provided with an outwardly-extending stud or journal 10, lying between two arms 11, extending upwardly from a bearing-block or casting 12 resting upon the road-bed. The block or casting 12 is recessed or provided with a concavity in its upper face forming a bearing in which the rolls are adapted to turn, and the arms 11 projecting upwardly therefrom are provided with inwardly-projecting lips 13 for engaging the base of the rail, which rests upon a horizontal ledge 14, or pair of such ledges formed integrally with and projecting slightly above the main body of the block or casting 12. A similar block or casting is located beneath and supports the roll 6, and the latter is provided with an outwardly-extending shaft or arm 15, having a crank-arm 16 formed thereon or secured thereto. All of the series of rolls 6 are similarly provided with crank-arms 16, and said crank-

arms are all pivotedly connected with a long rod or bar 17, which is connected at one end to the lower end of the switch-lever 18 by means of an interposed link 19, by means of which, 5 when the switch is vibrated, all of the rolls of both series will be simultaneously operated. The switch-lever may be of any desired form and is pivoted to and supported by a switch-stand 20 in the usual manner.

10 Each one of the rolls 6 and 7 is provided with a central depression or flattened portion 21, and the relative arrangement of the depressions is such that when, for instance, the depression 21 in the roll 6 is on the upper 15 side of said roll the corresponding depression in the roll 7 will be turned to one side or one-quarter of a revolution from the depression in the roll 6. The rolls 6 are all arranged in the same relation to each other, so that the 20 depressions therein will all occupy the same position at the same time, and the depressions in the roll 7 are likewise similarly arranged. The free ends of the split rails are located in line with such depressions, and are adapted 25 to rest in said depressions when the rolls are turned in the proper position. The split rails at their free ends are normally held down or depressed below the heads of the adjacent rails by means of strong springs 22, secured 30 beneath the angle-irons 3, and anchored to the road-bed in any suitable manner.

By throwing the switch-lever in the direction indicated in Fig. 1, by means of the interposed mechanism, above described, the depressions in the roll 6 are turned upward to receive the base of the split rail 1, thus permitting the upper face thereof to be drawn down by the spring 22, referred to. Simultaneously the rolls 7 operate against the base 40 of the rail 2, elevating its upper face or head into the same horizontal plane with the adjacent rail. Under this adjustment the main track is left unobstructed, and the flanges of the wheels are adapted to pass above the upper face or head of the split rail 1 and entirely clear thereof.

By throwing the switch-lever in the opposite direction the rolls 6 and 7 are caused to assume the position indicated in Fig. 2—that is, the depressions 21 in the rolls 7 will be brought uppermost to receive the base of the rail 2 and allow the head thereof to be depressed, and simultaneously therewith the rolls 6 will operate upon the base of the rail 1 55 and elevate its upper face or head into the same horizontal plane with the adjacent rail. Under this adjustment the switch is closed and the inner edge of the split rail 1 will engage the wheel-flanges and direct the engine 60 or car onto the siding, the upper face or head of the rail 2 being depressed to a point where it will be impossible for it to interfere in any way with the wheel-flanges, the latter passing above and entirely clear of the same.

65 23 indicates the locking-lever pivoted to a suitable stand 24, and connected at its lower end with a lever 25 by means of an interposed

link 26. The lever 25 passes beneath the rail and is pivoted intermediate its ends at 27. At its inner end, centrally between the two 70 rails, the lever 25 is provided with a sliding arm 28 pivoted thereto at one end, and provided at its other end with a notch or recess 29, which is adapted to engage the bar 8, which connects the rolls 6 and 7. When in engagement the notch or recess 29 in the bar 28 prevents the rolls from being turned in either direction, thus firmly locking the switch in a manner that will be readily understood.

75 30 indicates a semaphore of any ordinary 80 form or construction, provided near its lower end with a double crank from which a pivoted link or bar extends to and connects with the lower end of the switch-lever 18, whereby the said semaphore is operated simultaneously 85 with the opening and closing of the switch. In order to secure a snug joint between the ends of the split rails and the adjacent rails the latter are cut out, as shown at 31, in the base-flange, to receive and permit the up and 90 down movements of the free ends of the rails 1 and 2.

95 By means of the construction above described the switch may be operated with great ease and certainty. By reason of the depression of one or the other of the rails 1 and 2 it will be impossible for such depressed rail to engage and act upon the wheel-flanges, thereby entirely obviating all danger of derailment.

100 It will be apparent that the switch cannot become inoperative by reason of snow and ice, &c., becoming packed between the adjacent faces of the rails, as by the vertical movement of the split rails all accumulated ice, snow, &c., will be scraped off, constituting a great 105 advantage over the ordinary form of switch.

110 Various changes in the form, proportion, and the minor details of construction may be resorted to without departing from the principle or sacrificing any of the advantages of 110 this invention.

Having thus described my invention, I claim—

1. In a railway-switch, the combination with the point rails left free vertically at their extremities, of a series of cylindrical rolls arranged beneath the same and cut away or formed with depressions in their cylindrical faces adapted to receive the bases of said rails, said depressions being disposed in such 115 manner that one of the point rails will be elevated at the same time that the other is lowered, said rolls being coupled together in pairs, means for simultaneously operating each pair of rolls, and a bearing-block for and arranged 120 beneath each roll, said block having a concave seat for its respective roll and also comprising one or more extensions for engaging the base of a rail, substantially as specified.

2. In a railway-switch, the combination with two point rails left vertically free at their extremities, of a plurality of rolls underlying and supporting said rails, crank-arms connected with said rolls, a connecting-bar and

- switch-lever for simultaneously operating said rolls, and a supporting-block for each of said rolls, said block being contracted at one end to form a bearing for the gudgeon of said roll and also comprising a pair of oppositely-disposed and upwardly-projecting hooked extensions for engaging the base of the rail, all arranged for joint operation, substantially as described.
10. 3. In a railway-switch, the combination with two split rails left free vertically at one end, of the inwardly-projecting arms or irons 3, the interposed bolt and spring connecting said irons, and means substantially as described for elevating and lowering the free ends of the rails alternately, substantially as described.
15. 4. In a railway-switch, the combination with the split rails left free vertically at one end, of a plurality of rolls arranged in pairs, adapted to alternately raise and lower said rails, the interposed bar or shaft connecting the rolls of each pair, and an adjustable arm and lever for engaging and holding the rolls against rotation, all arranged and adapted to operate in the manner and substantially as described.
20. 5. In a railway-switch, the combination with
- two split rails left free vertically at one end, of the inwardly-projecting connecting arms or irons 3, the interposed bolt and spring connecting said arms, and a pair of oppositely-disposed springs connected with said arms or irons and operating in such manner as to permit either of said split rails to be raised or lowered independently of the other, substantially as described.
25. 6. In a railway-switch, the combination with the split rails left free vertically at one end, of a series of rock-shafts adapted to alternately raise and lower said rails, the interposed bar or rod connecting said rock-shafts for operating them simultaneously, an adjustable locking-arm 28 adapted to be moved into and out of engagement with one of said rock-shafts for locking the latter against rotation, and an operating-lever for adjusting said locking-arm, substantially as and for the purpose specified.

In testimony that I claim the foregoing as my own I have hereto affixed my signature in the presence of two witnesses.

FRANK JEWELL.
